No 2539

John Schumann

Design for the handles of spoons, knives and other articles of table furniture.

Patented

Jan 1 1887

John Schumann

United States Patent Office.

JOHN POLHAMUS, OF NEW YORK, N. Y.

Design No. 2,539, dated January 1, 1867.

DESIGN FOR THE HANDLE OF A FORK OR SPOON.

The Schedule referred to in these Letters Patent and making part of the same.

TO ALL WHOM IT MAY CONCERN:

Be it known that I, JOHN POLHAMUS, of the city and State of New York, have invented or produced a new and original Design for the Handles of Forks, Spoons, and other articles of table furniture; and I do hereby declare the following to be a full and clear description of the same, reference being had to the annexed photograph, representing my said design as formed upon the handle of a spoon.

At the end of the handle the design consists of an oval, *a*, with beads around it, the extreme end being in the form of a scallop or shell at *b*. On the handle adjoining the oval *a* is a tapering ornament with a cored ground and honeysuckle blossom ornaments, as at *c*. The handle is beaded upon its edges. Near the junction of the handle and bowl is an ormanent at *d*, generally resembling the ornament at *e*, but smaller. On the back of the spoon or fork, or similar article, is a heart-shaped ornament, with scroll beads and honeysuckle flower ornaments, as at *e*, and a spear-head ornement, *i*, extends from the said heart-shaped ornament up the shank of the handle.

What I claim, and desire to secure by Letters Patent, is—

The design for the handle of a fork, spoon, or similar article, as shown and described.

Dated this 27th day of November, A. D. 1866.
